UNITED STATES PATENT OFFICE.

ELBERT I. HUNTER, OF STEPHENVILLE, TEXAS.

ENGINE.

1,149,521.

Specification of Letters Patent. Patented Aug. 10, 1915.

Application filed April 18, 1914. Serial No. 832,839.

To all whom it may concern:

Be it known that I, ELBERT I. HUNTER, citizen of the United States, residing at Stephenville, in the county of Erath and State of Texas, have invented certain new and useful Improvements in Engines, of which the following is a specification, reference being had to the accompanying drawings.

10 This invention relates to improvements in gas engines and more particularly to an improved construction and arrangement of the engine cylinders in pairs, each of said cylinders being provided with a piston therein, 15 said pistons being arranged upon a common operating rod connected to the crank shaft, the driving force being applied simultaneously to the piston heads at the corresponding sides thereof whereby the crank 20 shaft is continuously and positively driven.

The primary object of the invention resides in the provision of improved means for mounting the pistons in the engine cylinders and admitting the explosive charge simultaneously to the corresponding ends of said cylinders whereby, in the event that the charge in one cylinder is not ignited, the explosion of the charge in the other cylinder will operate upon the piston therein and 30 thus insure the transmission of a positive driving force to the engine shaft.

My invention has for a further object to provide an improved construction of gas engine which is extremely simple, may be 35 manufactured at small cost and is highly reliable and efficient in practical operation.

With the above and other objects in view as will become apparent as the description proceeds, the invention consists in certain 40 constructions, combinations and arrangements of the parts that I shall hereinafter fully describe and claim.

For a full understanding of the invention, reference is to be had to the following 45 description and accompanying drawing, in which—

Figure 1 is a longitudinal section through the connected engine cylinders showing the arrangement of the pistons therein. Fig. 2 50 is a section taken on the line 2—2 of Fig. 1; Fig. 3 is an enlarged detail view of the piston rod.

Referring in detail to the drawings, 5 designates the spaced engine cylinders which 55 are provided with water jackets 6. The op-

posed ends of these cylinders are connected by the concentrically arranged sleeves 7 and 8 which are integrally formed with the hollow circular heads 9 at their ends, said heads being secured to the ends of the respective 60 cylinders. These spaced sleeves and the heads 9 provide an additional water space 10. The outer end of each cylinder is also provided with a head 11 having a water space 12. The head 11 on one cylinder is 65 formed with a double walled stem or sleeve 13, said walls at their outer ends being integrally connected to close the water space between said sleeves.

The piston rod indicated at 14 is mounted 70 for longitudinal reciprocatory movement through the inner tubular sleeve 8 between the engine cylinders and through the double-walled stem or sleeve 13 on the cylinder head 11. Upon one end of this rod, the piston 75 head 15 is arranged, said head engaging a stop flange or collar 16. The extremity of the rod is threaded to receive a nut 17 whereby the piston head is retained in connection with said rod. A second piston head 80 18 is also arranged upon the rod 14 for operation in the other of the engine cylinders, said rod having a threaded portion intermediate of its ends to receive a sectional nut 19 whereby the piston head is held against 85 an annular flange or collar 20 on said rod. At the proper point on the piston rod 14, the same is formed with the spaced peripheral flanges 21 between which suitable packing rings 22 are adapted to be arranged. These 90 packing rings frictionally engage the wall of the sleeve 8 and the inner wall of the sleeve 13 respectively for a purpose which will be obvious.

Intake and exhaust ports 23 are provided 95 in the opposite ends of each cylinder. 24 designates valve chambers with which the respective ports communicate. Each of the valve chambers 24 is provided with an intake and exhaust valve (not shown). The 100 valve chambers 24 are connected by pipes 25 to a manifold 26 which in turn is connected to a carbureter 27. This manifold is provided with the usual valve operated from the governor of the engine whereby the quantity 105 of gas supplied to the engine cylinder is automatically regulated in accordance with the load. Each of the valve chambers 24 is further provided with a spark plug 110 whereby the charge is exploded. Suitable

oil supply means is also provided to supply oil to the bearings of the piston rods in the sleeves 8 and 13.

In the practical operation of the engine, 5 the gas having been admitted to the corresponding ends of the respective cylinders, and compressed by the pistons 15, the charges are simultaneously exploded so as to reverse the movement of the pistons 15 10 and 18 in the respective cylinders. If the explosion fails to take place in one cylinder, the explosion of the gas in the other cylinder will insure the application of the driving force to the piston rod, so that the crank 15 shaft of the engine will be continuously driven. After the explosion in one end of the cylinder, the gas is admitted through the port at the opposite end of the cylinder so that the same will be compressed and when 20 the piston has completed its stroke, in one direction, this new charge is exploded to reverse the movement of the piston. It will thus be apparent that by providing the cylinders arranged in pairs and the double 25 piston, a maximum of driving force is obtained and the positive and continuous operation of the engine assured. It will also be appreciated that by the provision of the large water space, the engine cylinders and 30 pistons are rapidly cooled.

From the foregoing description taken in connection with the accompanying drawing, it is believed that the construction, manner of operation and several advantages of 35 my invention will be clearly and fully understood. The device is simple in its construction, positive and reliable in its operation and provides means whereby a continuous and steady power may be derived in the 40 use of explosive gas as the operating medium. It will of course be understood that the various accessories necessary in the successful operation of this type of engine will be provided, but as the same constitute no

part of the present invention, the specific 45 description thereof is deemed unnecessary.

While I have shown the preferred form and construction of the several parts employed, it will be understood that the invention is susceptible of considerable modification therein and I therefore reserve the privilege of resorting to all such legitimate changes as may be fairly embodied within the spirit and scope of the invention as claimed. 50

Having thus described the invention, what is claimed is:

1. In an engine, spaced engine cylinders, a double-wall sleeve having enlarged chambered ends detachably secured to the opposed ends of the cylinders and constituting heads therefor, a reciprocating piston rod movable through the bore of the sleeve, and pistons fixed upon said rod to reciprocate in the respective cylinders. 60

2. In an engine, spaced engine cylinders, integrally connected chambered heads detachably secured to the opposed ends of said cylinders, the connection between said heads having a longitudinal bore communicating 70 at its opposite ends with the respective cylinders, water jacketed heads secured upon the other ends of the cylinders, one of said heads having an elongated double walled sleeve integrally formed therewith, a piston rod extending through the bore of said connected heads and through said sleeve, packing rings secured upon said rod for frictional engagement with the wall of said sleeve and said bore respectively, and pistons fixed upon said rod to reciprocate in the respective cylinders. 75

In testimony whereof I hereunto affix my signature in the presence of two witnesses.

ELBERT I. HUNTER.
